GAS MIXER

Frank X. Bonem and Roy W. Bonam,
Detroit, Mich.

Application September 20, 1934, Serial No. 744,769

5 Claims. (Cl. 48—180)

This invention relates to gas mixers and the object of the invention is to provide a device to be positioned between the carburetor and the intake manifold of an internal combustion engine to admit additional air to the fuel mixture at the higher engine speeds to thereby effect economy in fuel consumption at constant engine speeds.

A further object of the invention is to provide a device of the character described which is fitted between the carburetor and intake manifold and in which the air inlet is automatically sealed at low engine speeds.

Another object of the invention is to provide a device of the character described which is automatically controlled in accordance with the suction produced by the speed of the engine.

A further object of the invention is to provide an automatic control of the character described in a flat member which may be readily mounted between the carburetor and intake manifold.

Another object of the invention is to provide a control bar which is moved by the suction produced at the higher engine speeds to open the air inlet.

These objects and the several novel features of the invention are hereinafter more fully described and claimed and the preferred form of construction by which these objects are attained is shown in the accompanying drawing in which—

Fig. 1 is an elevation of a carburetor and intake manifold showing our fuel economizer connected therebetween.

Fig. 2 is an enlarged perspective view of the fuel economizer.

Fig. 3 is an enlarged section taken on line 3—3 of Fig. 2.

Fig. 4 is a perspective view of a modified form of the fuel economizer.

Fig. 5 is an enlarged section taken on line 5—5 of Fig. 4.

Fig. 6 is an enlarged section taken on line 6—6 of Fig. 4.

Fig. 7 is an enlarged section taken on line 7—7 of Fig. 4.

The device is intended to be connected between the intake manifold 1 of an internal combustion engine shown in Fig. 1 and the outlet conduit 2 of a carburetor which may be of any standard type. The carburetor shown is provided with a bowl 3 and with an air cleaner 4 and is provided with a flange 5 which is of the same shape and size as the flange 6 of the intake manifold 1. As shown in Fig. 2, the fuel economizer comprises a metal plate 7 which is of substantially the same

shape as the flanges 5 and 6 of the carburetor and intake manifold and this plate 7 is provided with an extension 8 at one end. The plate 7 forms a cover plate for a thicker flat metal member 9 shown in Figs. 2 and 3. This member 9 is provided with a recess 10 to receive one end of the operating bar 11 which, as shown in Figs. 1, 2 and 3, extends diametrically across the central opening 12 in the member 9 and plate 7. This bar 11 is provided with a struck up rib 13 for strength 10 and a longitudinal recess 14 is provided in the extension 15 of the member 9 beneath the plate 8.

The bar 11 extends into this recess and is provided with a semi-spherical projection 16 which normally closes the inlet aperture 17 in the member 9. The plate 7 is provided with an upwardly pressed boss 18 and a spring 19 is positioned between the boss 18 and the projection 16 of the bar or arm 11. A gasket is positioned on the top and bottom of the device shown in Fig. 2 and the device with the gaskets is then fitted between the flanges 5 and 6 of the carburetor and intake manifold and these flanges are firmly secured together by tightening the screws 20 shown in Fig. 1. When so assembled, the portion 15 of the member 9 and the extension 8 of the plate 7 extend outwardly to one side of the flanges 5 and 6, as shown in Fig. 1.

The spring 19 is of sufficient strength as to prevent movement of the bar 11 under low engine speeds but as the engine speed is increased, the velocity of the fuel gas and air mixture flowing through the carburetor outlet and intake manifold will lift the bar 11 against the tension of the spring 19 thus opening the inlet port 17 and allowing air to flow through the recess 14 into the central opening 12 of the device where it is mixed with the fuel mixture and carried into the engine, not shown. As the engine speed again returns to low speed, the spring 19 forces the projection 16 back into the inlet port 17 thus shutting off the air inlet and allowing the engine to continue at low or idling speeds.

With the usual internal combustion engine, the carburetor is set to provide the proper mixture for low and idling speeds but as the speed of the engine is increased the mixture provided is richer than necessary to produce ideal engine operation and, consequently, the admission of additional air to the mixture at higher engine speeds produces better engine operation at these speeds and it also results in fuel economy due to the fact that the additional volume required by the engine is partly supplied by the additional air entering through the air inlet 17.

A modified form of the device is shown in Fig. 4 in which a member 21 is provided of the same shape as the member 9 and a recess 22 for the end of the bar 11 shown in Fig. 7 is cut into the member 21 by means of a key slot cutter. At the opposite end, a slot 23 is milled out of the extension 24, as shown in Figs. 5 and 6, and a plate 29 is in-set into the bottom of this slot while a plate 25 is in-set into the top of the slot. These plates may be pressed in place or welded in place, as desired, and the plate 29 is provided with an air inlet port 26 which is normally closed by the projection 16 of the arm 11 and the plate 25 is provided with an upwardly pressed boss 27 to receive the spring 19. In this case, the member 21 is made from one piece which may be a die casting, if desired, and the plates 29 and 25 are set into the die casting.

In both cases, the end of the bar 11 opposite the depression 16 is semi-floating, it being merely necessary to freely support this end in order to allow the action to take place between the projection 16 and the air inlet port. By this arrangement, the bar 11 will remain in position to close the air inlet port even though it is semi-floating but upon increased engine speeds the bar is lifted upwardly against the tension of the spring 19 to open the air inlet port and allow additional air to enter the central opening 12 and mix with the fuel vapor or gas and air mixture passing therethrough.

From the foregoing description it becomes evident that the device is very simple and efficient in operation, will not easily get out of order, is composed of few parts and is of consequent low manufacturing cost and provides a device which accomplishes the objects described.

Having thus fully described our invention, its utility and mode of operation, what we claim and desire to secure by Letters Patent of the United States is—

1. In a gas mixer for use between the intake manifold and the carburetor of an internal combustion engine, a member shaped to fit between the carburetor and intake manifold and having an aperture registering with the conduits of the carburetor and intake manifold, a non-pivoted bar extending across the aperture of the said member, said member having recesses on diametrically opposite sides opening to the aperture of the member and of a width transversely of the bar greater than the thickness of the bar and in which the respective ends of the bar lie, the bar being provided near one end with a projection and the member being provided with an air inlet port opening to the recess for that end of the bar having the projection, a spring normally holding the bar in position with the projection closing the air inlet port, the arrangement being such that the velocity of the mixture passing the bar upon reaching a pre-determined point will lift the bar bodily against the spring to the extent allowed by the spring and width of the recesses and open the air inlet port.

2. In a gas mixer, a flat member adapted to be secured between the carburetor and intake manifold of an internal combustion engine, said flat member being provided with an aperture registering with the conduit of the intake manifold, a non-pivoted bar extending across said aperture, the flat member being provided with an extension at one side having a recess open at one end to the aperture of the member into which the bar extends, the bar being provided with a projection in said end, the recess for the flat member being provided with an air inlet port, and a spring normally pressing the projection to position to close the air inlet port.

3. In a device of the character described, a substantially flat member having a circular opening, said member being provided with an extension at one side and the extension being provided with a recess communicating with said central opening, a bar extending into said recess and across the central opening, the extension being provided with an air inlet port opening into the recess, a projection on the bar normally fitting said inlet port, and a spring holding the bar in position to engage the projection in the inlet port, the arrangement being such that a pre-determined pressure against one side of the bar will raise the bar against the spring to the extent allowed by the width of the recess and open the inlet port.

4. In a device of the character described, a substantially flat member having an opening therethrough and an extension at one side of the opening, the extension being provided with a recess communicating with the said opening and the flat member being provided with a second recess on the side of the opening diametrically opposite the first recess, a bar extending across the opening into both recesses, the end of the bar in the recess of the extension being provided with a projection, the extension being provided with an air intake port opening into the recess, and a spring normally pressing the projection of the bar into the air intake port, the spring being arranged to allow the bar to raise when a pre-determined pressure is applied thereto.

5. In a device of the character described, a member having a central opening, a flat sheet metal bar extending diametrically across the central opening, one end of the bar being provided with a projection and said member having a recess in communication with the central opening in which the end of the bar lies, the said member being provided with an air intake port normally closed by the projection of the bar, a coil spring engaging the bar opposite the projection and resisting movement of the bar by air flow through the said central opening of the member and said air intake port being in communication with the central opening of said member.
